UNITED STATES PATENT OFFICE

143,646

DESIGN FOR A CAN OPENER

James Harvey Chandler, Oak Park, Ill., assignor to Ekco Products Company, Chicago, Ill., a corporation of Illinois

Application January 17, 1945, Serial No. 117,473

Term of patent 14 years

(Cl. D22—2)

To all whom it may concern:

Be it known that I, James Harvey Chandler, a citizen of the United States, residing at Oak Park, in the county of Cook and State of Illinois, have invented a new, original, and ornamental Design for a Can Opener, of which the following is a specification, reference being had to the accompanying drawing, forming part thereof.

Fig. 1 is a side elevational view of a can opener showing my new design.

Fig. 2 is an end view of the can opener as the same would appear from the left side on Fig. 1.

Fig. 3 is a top plan view thereof.

The dominant feature of this design resides in the portion shown in full lines.

I claim:

The ornamental design for a can opener, as shown.

JAMES HARVEY CHANDLER.
